FOLDING STAND

Filed Sept. 24, 1927

Inventor:

Roscoe H. Hiatt;

By *Robert W. Sandle*,

Attorney.

UNITED STATES PATENT OFFICE.

ROSCOE H. HIATT, OF GREENSFORK, INDIANA.

FOLDING STAND.

Application filed September 24, 1927. Serial No. 221,708.

The object of this my present invention, broadly speaking, is the provision of a folding stool or stand which is simple in construction, strong and durable in its several parts, 5 easily operated to open and close, efficient in practice, adapted to a variety of uses, which will occupy but a minimum of space, economical of transportation, and which can be manufactured and sold at a comparatively low 10 price.

More specifically stated, my object is to provide a stand which is especially adapted to support a basket or the like having a rounded bottom, which basket can not inadvertently 15 slip off the stand, but by which the basket can be supported in either upright or in tilted position, and by which the basket can be supported at either one or more elevations; the stand also being adapted to support a box or 20 a tub or other article, even though the bottom be not rounded; and at the time being adapted to support a comparatively great weight.

Other objects and particular advantages 25 of my invention will suggest themselves in the course of the following specification. The preferred means for carrying out the principles of my invention in a practical and efficient manner is shown in the accompanying drawings, in which—Figure 1 is a perspective view of my complete stand alone and in folded condition. Figure 2 shows the stand 30 opened out and showing a basket supported thereby in tilted position. Figure 3 shows my stand open but reversed with relation to Fig. 35 2, and showing a basket supported thereby in upright position. Figure 4 shows the stand in the same position as in Fig. 2 but showing a tub supported thereby. And Figure 5 is a cross section, as taken, for instance, on the 40 line 5—5 of Fig. 1.

Similar indices denote like parts throughout the several views.

Merely for convenience in description, and for clearness of comprehension, I will herein 45 refer to the stand as it is shown in Figs. 1, 2 and 4 as in upright position; while as that shown in Fig. 3 I will refer to as in reversed or inverted position, that is turned upside down. Also in the description reference is 50 made to upper and lower parts, or similar terms, it will have reference to the position of the stand as it is shown in Figs. 1, 2 and 3.

As the three main members of the device 55 are identical with each other in every particular, therefore, to avoid prolixity of de-

scription, corresponding parts in each will be designated by like indices and a description of one of the main members will answer for all.

I will now take up a detailed description of my invention, in which I will set forth the same as fully and as comprehensively as I may.

This invention includes three, or more, main members which are identical with each other, each being substantially trapezoidal in contour and each formed, in this instance, of a single length of round-iron, or rod, which is bent into substantially the shape shown and each including a vertical leg-portion 1 and a vertical stem portion 2, which parts are parallel with each other but are spaced apart, with the center of the stem 2 located above the center of the leg 1; that is,—on a higher level.

Extending outward and upward, in a curve, from the stem 2 is the upper or short arm member 3, which connects with the upper and inverted U-shaped contact member 4, formed by the union of the outer part of the arm 4 and the upper part of the leg 1.

Likewise, extending outward and downward, in a curve from the lower end of the stem 2, is the long or lower arm member 5, which connects with lower U-shaped contact member 6, formed by the union of the outer part of the arm 5 and the lower part of the leg 1.

The member 1 is formed double throughout the greater portion of its length, which 90 is accomplished simply by twisting together the two parts of which the main member is formed.

Each of the main members is formed by first securing the part of a rod which is to form the stem 2, then bending the arms 3 and 5, and next the U-shaped contacts 4 and 6, and the remainder of the end portions of the material which will then lie parallel with each other are then twisted together, as shown, thereby forming the leg portion 1, and thereby forming a very rigid construction.

In order to assemble, three or more of the main members are placed together, as in Fig. 1, and stem portions thereof are then inclosed 105 in the collar 7 which forms a hinge portion, with each of the stems rotatable independently of each other.

Said collar 7 may be formed of a plate 110 of sheet metal pressed around the three stems

2 or, preferably, it may be of flattened tubular construction, as shown, and if of the latter construction then the three rods intended to form the three main members, must be inserted in the collar 7 before they are bent, as stated above.

In the drawings the letter A denotes the outline of a rounded bottom basket, such as is intended to be used with my stand. Letter 10 B designates the outline of a tub, and letter C denotes the floor on which my stand rests.

Operation: When opened out, that is with the three main members spaced equidistance apart, the stand may be placed in operative 15 position with the three contact members 6 resting on the floor C. The basket A is placed in position, nesting on the arms 3, with the basket in either upright, or in tilted position 20 as in Fig. 2, whereby the goods contained in the basket may be readily shown and at the proper height, both for examination and for protection from damage. Another one of my stands may be placed in front of the first stand, with the second stand reversed, that 25 is with the contacts 4 resting on the floor C, with a second basket placed on the second stand, as in Fig. 3. This, of course, will bring the second basket slightly lower than the first basket, and thereby making the display more 30 convenient and effective.

If my stand be used to support a tub B then either end of the stand may be uppermost and

the tub, or other article, will rest on contacts 4, or 6, which ever happens to be uppermost.

When not in use the stand may be folded, 35 as in Fig. 1, when it may be hung up out of the way for future use.

It is evident that when folded a great number of my stands may be placed in a comparatively small space for shipment, or storage. 40

I desire that it be understood that various changes may be made in the shape and other details herein shown without departing from the spirit of my invention or sacrificing any 45 of the advantages thereof which are new and useful.

Having now fully shown and described my invention, what I claim and desire to secure by Letters Patent of the United States, 50 is—

A stand comprising a plurality of main section members which are identical with each other, each of said members being formed by a metal rod forming a stem member and a leg member parallel with each other, the 55 leg member being formed by the end portions of the rod twisted together with the center of the stem member on a level different from that of the center of the leg member, and means for pivotally connecting the stem members. 60

In testimony whereof I have hereunto subscribed my name.

ROSCOE H. HIATT.
